UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

TUBE FRAME.

Application filed June 1, 1922. Serial No. 565,141.

To all whom it may concern:

Be it known that I, EDGAR F. HATHAWAY, a citizen of the United States, and resident of Wellesley, in the county of Norfolk and State of Massachusetts, have invented certain new and useful Improvements in Tube Frames, of which the following is a specification.

This invention relates to tube frames such as are commonly employed for introducing tufts of yarn between the warp threads in the weaving of pile fabrics such as Axminster carpets.

As is well known by those skilled in the art, such tube frames comprise essentially a longitudinal carrier bar forming the backbone of the tube frame and is provided at its opposite ends with substantially parallel vertical arms formed with bearings for the yarn spool, and also constructed and arranged to be connected with, and disconnected from a carrier comprising parallel sprocket chains from which the tube frame is removed automatically by a pair of transfer clutches and to which the tube frame is returned after it has been used to supply the row of yarn tufts which are fed through individual tubes or hollow needles mounted along the carrier bar to supply a row of tufts to the fabric.

Heretofore the common practice has been to employ at each end of the tube frame, carrier bar a pair of suspension arms, one of which is of spring material and is provided with a hook for overlapping the top of the supporting chain link from which it can be removed by springing the hook away from the companion arm. In view of the fact that hundreds of these tube frames have to be carried successively into position for transfer to the loom for operation and then returned again, it is of great importance to secure perfect alignment between the suspension means and the supporting links of the carrier chain, but such spring arms as have heretofore been used easily get bent out of shape and thus cease to maintain the desired alignment for satisfactorily restoring the tube frame to the carrier chain. In a companion application filed March 6, 1922, and patented September 25, 1923, No. 1,469,180, I have shown improved suspension means for a tube frame in which both

arms are rigid but one of them is pivotally mounted or connected to the other and is actuated by a separate spring. The present invention is intended to secure perfect alignment between the two cooperating suspension members which are arranged at each end of the tube frame by using a pivotal connection between two substantially rigid arms but arranging the pivot arm or member to move about an axis, that is, transverse to the line of the carrier chain, instead of being parallel thereto such pivotal arm in this case forming in effect a swivel arm or button so constructed as to normally return in locking position while being capable of rotation by the movement of the transfer clutch from the carrier chains.

This and other features of the invention will be hereinafter described and will be defined in the claims hereto annexed.

In the accompanying drawings:

Figure 1 illustrates a front elevation partly in section of the suspension means in its relation to the carrier bar and to the transfer clutch.

Figure 2 is a plan view of the same.

Figure 3 is a view similar to Figure 1 with the suspension means in releasable position.

Figure 4 is a plan view of the parts as shown in Figure 3.

Figure 5 is an end elevation of the parts shown in Figure 3.

Figure 6 is a front elevation showing a modified form.

Figure 7 is a plan view thereof.

Figure 8 is a plan view on the sectional plane 8—8 of Figure 6.

Figure 9 is an end elevation showing the form of the blank and the folding lines thereof out of which is constructed the suspension arm attached to the carrier bar.

In the practice of this invention according to the form shown in Figures 1 to 5 inclusive, I provide a main suspension arm 1, having portions thereof inwardly turned to form parallel tongues 2 and 3, spaced apart to fit inside the tubular end of a carrier bar *a*. At its upper end the arm 1 is provided with an inwardly and upwardly extending perforated ear 4, to form a bearing support for the end journal of the usual yarn roller.

The main upper end portion of the blank is bent outwardly to form parallel horizontal arms 5, between which is located a block 6, provided at its middle portion with a vertical bearing orifice in which is pivotally mounted a cooperating suspension member 7 having its upper end formed in the shape of a pointed or tapered button 8, and having its lower end provided with a short actuating arm or finger 9 longitudinally slotted as shown at 10 to receive a projecting pin 11 mounted on a slide member or plunger 12, which is slideable outwardly and inwardly to one side of the pivotal axis of the member 7 and which is provided with an offset downwardly extending finger 12^a, whose lower portion comes opposite the line of the pivotal axis of member 7 below the level of the arm 9, and in position to be engaged by the inwardly projecting boss commonly formed at the upper end of the transfer clutch 15 which is indicated in dotted lines in Figures 1 and 3 and is of old and well known construction.

The tension spring 14, attached to the rear end 9^a of the arm 9, with its other end suitably secured to the main suspension arm 1, serves to normally pull the arm 9 in a contraclockwise direction as viewed in plan while allowing the arm to be shifted to the position indicated in dotted lines in Figure 4 when the transfer clutch 15 is raised and moved inwardly into operative engagement for releasing and transferring the tube frame from the carrier chains 16 by which it is fed into position above the loom.

The chain-overhanging portion 8, of the member 7, is adapted to penetrate a link of the chain when in the position shown in Figure 3 which is the position both for removing the tube frame from the chain and for re-inserting it by means of transfer clutches 15. In that position the actuating slide 12 has been pressed to its inmost position, leaving the head or hook portion 8 of member 7 extending lengthwise in the direction of the chain. Upon the outward movement of the transfer clutch 15, the tension spring 14, turns the member 7 through an arc of 90° so that the head or hook portion overhangs the chain link to prevent its withdrawal. This outward movement of the slide 12 is limited by the abutting of the arm 12^a against the inner end of the bearing block 6.

The simplified construction and arrangement embodying the same principle of action is illustrated in Figures 6 to 9 inclusive.

In this modified form of the invention the separate bearing blank 6, and the slide member 12, may be dispensed with and the transfer clutch 15 will act directly upon clutch-engaging means located at the lower

end of the swivel member 7, which swivel member is of the same construction as that previously described.

In this case the arm 1, with the fastening tongues 2 and 3 and with the spool-supporting ear 4, are formed as previously described. As shown in Figure 9, the extreme upper end of the blank out of which arm 1 is formed is partly cut away on either side edge to form a narrow connecting portion 75 or neck 20 leaving side wings or members 21 to be folded in as indicated by dotted lines to lie in parallelism and to project downward to form flanges when the upper end is bent outwardly at right angles along 80 the transverse dotted line of Figure 9 to form a supporting plate 22, which is really an offset support for the cooperating chain locking member 7. These downwardly projecting side flanges 21, have their interior 85 portions cut away to leave projections 23 for retaining a bottom bearing plate 24 in position to form a supporting or positioning bearing for the lower end of the member 7, said bearing plate 24 being centrally perforated in alignment with the bearing perforation formed at 25 in the horizontal extension 22 of the arm 1.

To the extreme lower end of the swivel member 27 is secured an actuating arm 26, 95 whose forwardly exposed face is in line with an upwardly projecting pin 15^a on the transfer clutch with exposed edge, as will be seen, is laterally offset from its central axis of rotation a distance equal to the offset distance of the pin ^a from the middle line of the transfer clutch. The transfer clutch moves in on a straight line until the pin reaches the position shown in dotted lines at the left of Figure 7 in which position the 100 actuating arm 26 will be turned just 90°, as indicated in dotted lines in Figure 7. This quarter turn of the member 7 brings the longitudinal axis of the head into alignment with the carrier chain link to permit withdrawal of the locking member 7 from the chain or to permit its insertion therein.

A tension spring 27, engaging the opposite end of the lever 26, tends to draw it in a contraclockwise direction so as to restore 115 the locking member 7 to locking position and keep it there until the arm 26 is swung around by the transfer clutch into releasing position. The pivoted locking member 7 is provided with a projecting collar or 120 flange 7^b, which is notched to form stop shoulder 7^c, 90° apart to engage an upwardly projecting stop pin 29 so as to limit the rotative movement of the member 7 to the desired arc of movement and prevent the 125 tension spring from pulling it beyond its proper locking position.

In Figure 8 the construction is the same as that above described except that the extreme lower end of the member 7 is pro- 130

vided with a disk or plate 30, carrying a downwardly projecting pin 31 arranged to be engaged with an oblique cam surface 32 formed on the upwardly projecting portion 5 of the transfer clutch 15. Obviously, as the cam surface advances bodily toward the central axis of member 7, its oblique surface, acting on the downwardly projecting pin 31, serves to revolve the pin about the axis 7 until it reaches the outside of the cam member 32 which is so designed as to secure just a quarter turn or rotation of the member 7. The tension spring 27 acts precisely as before to return the pivotal member 10 to its normal locking position after the transfer clutch has withdrawn from operative engagement.

What I claim is:

1. Tube frame suspension means embracing in its construction, a pair of cooperating suspension members pivotally connected together about a pivotal axis extending on a line transverse to the tube frame carrier chain one of said members being formed 20 to releasably interlock with said carrier chain, substantially as described.

2. Tube frame suspension means embracing in its construction an upright arm firmly secured to the carrier bar of a tube frame, a swivel locking member mounted at the upper end of said arm in position to overhang the tube frame carrier chain when in locking position, and means connected with said swivel member arranged to 30 be operated by the loom transfer clutch to shift said swivel member to position to permit withdrawal of the tube frame from its carrier, substantially as described.

3. Tube frame suspension means embracing in combination with a carrier chain, a 40 suspension member adapted to form a suspending connection between the chain and the tube frame, a spring-actuated slide member acting to maintain said suspension member against movement from its operative suspending position, said slide member being arranged to be shifted against the action of its spring by approaching transfer mechanism to permit release of the suspending connection in order to allow transfer of the tube frame from the chain to the loom, substantially as described.

4. The combination with a tube frame carrier chain, a tube frame transfer mechanism, 50 of tube frame suspending means forming a releasable suspending connection between the tube frame and the chain, a spring-actuated slide bolt normally acting to prevent release of such suspending connection while adapted to yield under pressure of the transfer mechanism to permit the transfer mechanism to withdraw the tube frame from its suspended connection with the chain and transfer it to the loom, substantially as described.

5. A tube frame suspension device em-

bracing in its construction a suspension arm secured to the tube frame, a spring pressed chain engaging member mounted at the upper end of said arm and movable about a vertical axis into and out of locking engagement with the tube frame carrier chain, and means arranged to be engaged by the tube frame transfer clutch to move the chain engaging member about a vertical axis into position to permit release from the carrier chain, substantially as described.

6. A tube frame suspension device embracing in its construction, a suspension arm secured to the tube frame, a swiveled chain-penetrating locking member mounted at the upper end of said arm for releasably locking the tube frame to its carrier, and a spring arranged to normally shift the locking member to locking position while permitting it to be moved to releasing position 85 when actuated by the tube frame carrier clutch.

7. A tube frame suspension device embracing in its construction cooperating suspension members one of which is constructed and arranged to penetrate a link of the tube frame carrier chain and to be rotated therein to chain-locking position, and to be shifted to position for release by the action of the tube frame transfer clutch, substantially as described.

8. A tube frame suspension device embracing in its construction a suspension arm secured to the tube frame, a chain penetrating member pivotally mounted thereon and rotatable to locking position after insertion in a link of the chain, and means whereby the chain penetrating member is turned to releasing position by the action of the tube frame transfer clutch.

9. A tube frame suspension device embracing in its construction two suspension members comprising an arm rigidly connected to the tube frame and a relatively movable member mounted at its upper end 110 to form connection with the tube frame carrier chain, the latter of said members being formed to penetrate a link of the carrier chain, and being movable to releasing position by the action of the tube frame transfer clutch.

10. A tube frame suspension device embracing in its construction a suspension arm secured to the tube frame and provided with an offset portion disposed to underlie the tube frame carrier chain, a cooperating member pivotally supported by said offset portion to penetrate an overhead chain link, said pivotal member being provided with a projecting arm adapted to be moved about its pivotal axis by the inwardly moving tube frame transfer clutch to turn the pivotal member to position for withdrawal from the chain link, substantially as described.

11. A tube frame suspension device em-

bracing in its construction a suspension arm adapted to be secured to the tube frame, a link penetrating cooperating member pivotally mounted thereon for rotation into and out of locking relationship to the tube frame carrier chain, an arm secured to the lower end of said link-penetrating member

to turn it from locking to releasing position, and a slide operatively related to said arm in position to be engaged and actuated by the transfer clutch of the tube frame.

In witness whereof, I have subscribed the above specification.

EDGAR F. HATHAWAY.
